UNITED STATES PATENT OFFICE

GEORGE LYMAN ARMS, OF CHICAGO, ILLINOIS, ASSIGNOR TO ROBERTS AND SCHAEFER COMPANY, OF CHICAGO, ILLINOIS, A CORPORATION OF ILLINOIS

METHOD OF DISTRIBUTING AND CIRCULATING AIR FOR AIR CLEANING TABLES

Application filed May 18, 1928. Serial No. 278,685.

My invention relates to improvements in method of distributing and circulating air for air cleaning tables. It has for one object to provide a new and improved apparatus for and means for controlling and circulating the air which effects cleaning and separation without providing an excessively great quantity of air from which dust may be separated before it is discharged into the outer atmosphere. Another object of the invention is to make it possible to use large volumes of air for coal cleaning and treating and to remove the dust from such air without separately treating and dust cleaning the total amount of the air in the system. Other objects will appear from time to time throughout the specification and claims.

My invention is illustrated more or less diagrammatically in the accompanying drawings wherein—

Figure 1 is a diagrammatic side elevation; Figure 2 is a section along the line 2—2 of Figure 1.

Like parts are indicated by like characters throughout.

The coal treating, separating air cleaning plant is of the type well-known to the art wherein there are a plurality of coal cleaning tables, it being understood that the coal is classified as to size before being fed to the tables and each table receives coal mixed with the refuse as it comes from the mine of a size for each table conforming to the general character of the table. It will be understood that the table which treats the small or fine coal particles requires much less air than the table which treats the coarser particles, and the fine coal table is equipped with a small fine pervious screen deck, the other tables as they handle larger and larger sizes of coal being equipped with progressively increased sized screens forming the decks. It will further be understood that while absolutely pure air must be fed to the underside of the fine

deck, a certain amount of dust in the air as it is fed to the coarser decks is not felt.

A general description of one deck will suffice for all. The table unit comprises a blower A supplying air under pressure through a conduit A¹ to a funnel or évase chimney A² on the underside of a pervious deck A³. The air passes through this deck at relatively high velocity and passes through a continuously flowing sheet of material on the deck. The supporting means A⁴ are provided to adjust the angle of inclination of the deck and the linkage A⁵ is provided to support the deck and permit it to be reciprocated by the eccentric wheel A⁶, connecting rod A⁷ the wheel being driven through a gear train A⁸ from the fan shaft, which in turn is driven by a motor A⁹. A¹⁰ is a feed hopper discharging through the chute A¹¹ onto the surface of the deck, the mixed coal and refuse supplied by any suitable conveyor A¹². It will be understood that the purpose of the deck is to separate the coal and the refuse by gravity.

Located above each deck is a hood B, there being a flexible bellows B¹ extending down from the hood to and engaging the deck to make a generally dust tight joint between the reciprocating deck and the fixed hood but there must be space between the deck and the hood through the bellows for the admission of coal and refuse to be treated and for the discharge of the separated coal and refuse. B² is a suction pipe leading from the top of the hood through a settling chamber B³. These features are the same in all the tables except for difference in size to take care of differences in the air volume passing through or handled by the various tables.

I have numbered the tables from right to left as 1 to 5 inclusive. Number 1 is the finest table and the other tables increase in coarseness of screen and by material treated by them and increase in air requirements from 1 to 5 though it will be understood that a greater or less number of tables might be used.

C is an air cleaner through which air is drawn to the fan A for table Number 1. In the example which I have shown this table requires 4,000 cubic feet of air. This air is cleaned before it is forced through the screen because if there were dust in the air it would clog the fine screen. The spent air above the table under the hood B is drawn out through the pipe B² into the dust settling chamber though this chamber might be dispensed with if that were desired and then drawn through a suction pipe C¹, which pipe carries 4,000 feet of air plus the amount of air which enters in through the bellows between the deck and hood on the fine table. This approximately 4,000 feet is drawn into the fan which feeds air to Number 2 table. This table requires 6,000 feet of air, 4,000 plus the make-up air as I prefer to call it, entering between the hood and deck on the fine table and comes to the fan through the pipe C¹. The plant to make up the 6,000, that is 2,000 feet less make up enters the fan A for the second table through an adjustable intake opening C². The 6,000 feet of air passes up through the pipe A¹ in the funnel and deck to the hood as above pointed out. From the hood B is drawn through the pipe C³, 6,000 cubic feet of air plus make-up from table Number 2. This 6,000 feet of air is discharged into a make-up manifold C⁴, the pipe C³ discharging into the fan A associated with Number 3 table. This pipe C³ discharges 6,000 cubic feet of air. The deck itself needs 9,000. In this case to avoid drawing in an excess of make-up air the dust laden air is recirculated from the hood B associated with Number 3 table through a recirculation pipe C⁵ which pipe also discharges into the manifold C⁴. This pipe will discharge into the manifold 3,000 feet less make up so that a total of 9,000 feet is discharged to the deck. The control valve C⁶ is provided to add if necessary an additional supply of air to the make-up manifold to insure that the proper amount of air is fed to the deck. This make-up manifold and control valve is found in connection with tables Nos. 4 and 5 also.

From the hood B of table No. 3 is withdrawn through the settling chamber and through the pipe C⁷ only 6,000 feet plus make up. 3,000 feet is recirculated between the hood and fan of No. 4 from the pipe C⁸ and 3,000 feet is introduced controlled by the valve C⁶ to give a total 12,000 feet of air to work the table. From the hood of table No. 4 is drawn 9,000 feet of air through pipe C⁹ to the make-up manifold of table No. 5. 3,000 feet is recirculated through the pipe C¹⁰ and only 4,000 feet is drawn off through the pipe C¹¹ to the dust separating apparatus C¹².

It will be understood, of course that these amounts are only generally stated. There may be considerable divergents in any particular set of tables between make-up recircu-

lation and transfer from one table to another because this apparatus must be set up to take care of the peculiar characteristics of the coal which is treated and because every operator who adjusts or sets up the plant is likely to make slightly different adjustments from the other but however those adjustments are made, it always results in maintaining that part of the system between the fan and the deck under pressure and the balance of the system under suction so that all leakage is inward. The dust is always thus kept in the system and the dust in the air forced through any table except the smallest one is some of it deposited with the coal passing through the table. The remainder only that which is carried out with the 4,000 feet or relatively small amount fed to the dust separator is the only dust which gets out of the system except with the coal and slate as it is discharged.

Experience shows that there is a limit beyond which the air is enabled to carry dust so that when the air reaches the dust saturated point any additional dust is deposited on the coal or settled out through the settling chambers. The reason for using the settling chambers is to provide means for recovering the coal dust which is valuable and to make it unnecessary to circulate through the system and through the fan large and heavy quantities of dust and to prevent discharging from the tables excessively dusty coal which would be dirty to handle in the plant but as far as the operation of the settling chamber is concerned the dust settling chambers could be dispensed with.

It will be understood that while I have shown a complete system taking care of five differing tables handling coal of five different sizes, nevertheless my system might be applied to a larger or to a smaller number of tables and under some conditions recirculation of the coal between the hood and the fan of every table and under other conditions no recirculation need be used or in other conditions only recirculation at the end of the system might be the best solution.

I claim:

1. The process of cleaning coal by air which consists in forcing a high pressure stream of air through a flowing bed of coal adding a supply of additional air to the dust laden air above the bed, withdrawing the resultant air from above the bed and forcing such air under high pressure through a second flowing bed of coal the beds of coal as far as the circulation of the air is concerned being arranged in series.

2. The process of cleaning coal by air which consists in forcing a high pressure stream of air through a flowing bed of coal adding a supply of additional air to the dust laden air above the bed, withdrawing the resultant air from above the bed, and recirculat-

ing part of such air through the bed and forcing the remainder through a second flowing bed of coal the beds of coal as far as the circulation of the air is concerned being arranged in series.

3. The process of cleaning coal by air which consists in providing a plurality of separate flowing beds of coal, forcing a high pressure stream of air through each bed, adding a supply of additional air to the dust laden air above each bed, withdrawing the resultant air from above each bed, recirculating part of the air from some of said beds through the bed from above where it is withdrawn and forcing the remaining air from some of said beds through an adjacent bed the beds of coal as far as the circulation of the air is concerned being arranged in series.

4. The process of cleaning coal by air which consists in providing a plurality of separate flowing beds of coal, forcing a high pressure stream of air through each bed, adding a supply of additional air to the dust laden air above each bed, withdrawing the resultant air from above each bed, the air supply to the first bed of the system being substantially free from dust, withdrawing all the resultant air from above the first bed and forcing it through the next bed in the system, withdrawing some of the air from above each other bed in the system and recirculating through the same bed and withdrawing some of the air from the last bed in the system and separately removing dust therefrom.

5. The process of cleaning coal by air which consists in providing a plurality of separate flowing beds of coal, forcing a high pressure stream of air through each bed, adding a supply of additional air to the dust laden air above each bed, withdrawing the resultant air from above each bed, the air supply to the first bed of the system being substantially free from dust, withdrawing all the resultant air from above the first bed and forcing it through the next bed in the system, withdrawing some of the air from above each other bed in the system and recirculating through the same bed and withdrawing some of the air from the last bed in the system and separately removing dust therefrom, and separating some of the dust from the air as it travels from above one bed before it is discharged through the next.

6. The process of cleaning coal by air which consists in providing a plurality of separate flowing beds of coal, forcing a high pressure stream of air through each bed, adding a supply of additional air to the dust laden air above each bed, withdrawing the resultant air from above each bed, recirculating part of the air from some of said beds through the bed from above where it is withdrawn and forcing the remaining air from some of said beds through an adjacent bed, and adding additional make-up air to the air received

from above each bed to make up the proper amount to be discharged to the next bed, the beds of coal as far as the circulation of the air is concerned being arranged in series.

7. The process of cleaning coal by air which consists in providing a plurality of separate flowing beds of coal, forcing a high pressure stream of air through each bed, adding a supply of additional air to the dust laden air above each bed, withdrawing the resultant air from above each bed, the air supply to the first bed of the system being substantially free from dust, withdrawing all the resultant air from above the first bed and forcing it through the next bed in the system, withdrawing some of the air from above each other bed in the system and recirculating through the same bed and withdrawing some of the air from the last bed in the system and separately removing dust therefrom, and adding additional make-up air to the air received from above each bed to make up the proper amount to be discharged to the next bed.

8. The process of cleaning coal by air which consists in providing a plurality of separate flowing beds of coal, forcing a high pressure stream of air through each bed, adding a supply of additional air to the dust laden air above each bed, withdrawing the resultant air from above each bed, the air supply to the first bed of the system being substantially free from dust, withdrawing all the resultant air from above the first bed and forcing it through the next bed in the system, withdrawing some of the air from above each other bed in the system and recirculating through the same bed and withdrawing some of the air from the last bed in the system and separately removing dust therefrom, and separating some of the dust from the air as it travels from above one bed before it is discharged through the next, and adding additional make-up air to the air received from above each bed to make up the proper amount to be discharged to the next bed.

9. The process of supplying air for an air cleaning bed of coal which bed is one of a plurality of beds in an air cleaning system wherein a blast of air is forced through the bed which consists in obtaining the air to form such blast partially by withdrawing it from a separate bed in the system, partially from withdrawing spent air from above the bed to which the air is to be forced and partially by drawing fresh air from outside the system the beds of coal as far as the circulation of the air is concerned being arranged in series.

10. The process of cleaning coal by air which consists in forcing a stream of air through a flowing bed of coal, drawing off the spent dust laden air from above the bed, entraining with it an additional supply of air, forcing the resultant dust laden air

through a second flowing bed of coal, drawing off the dust laden air from above the bed and entraining with it an additional supply of air and separating the dust from the air.

11. The process of cleaning coal by air which consists in forcing a stream of air through a flowing bed of coal, drawing off the spent dust laden air from above the bed,
10 forcing the resultant dust laden air through a second flowing bed of coal, drawing off the dust laden air from above the bed and separating the dust from the air.

Signed at Chicago county of Cook and
15 State of Illinois, this 14th day of May 1928.
